UNITED STATES PATENT OFFICE.

GEORGE C. McCONNELL, OF MASSILLON, OHIO, ASSIGNOR TO FIDELITY TIRE & RUBBER CO., OF MASSILLON, OHIO, A CORPORATION OF ILLINOIS.

DESIGN FOR A TIRE-TREAD OR SIMILAR ARTICLE.

55,190.

Specification for Design.

Patented May 18, 1920.

Application filed December 5, 1919. Serial No. 342,843. Term of patent 14 years.

To all whom it may concern:

Be it known that I, GEORGE C. McCONNELL, a citizen of the United States, and residing in the city of Massillon, in the county of Stark and State of Ohio, have invented a new, original, and ornamental Design for a Tire-Tread or Similar Article, of which the following is the specification, reference being had to the accompanying drawings, forming a part thereof.

On the drawings:

Figure 1 is a fragmentary view of a tire

tread illustrating the design embodying my invention.

Fig. 2 is a sectional view thereof taken on line 2—2 of Fig. 1.

I claim:

The ornamental design for a tire tread or similar article as shown.

GEORGE C. McCONNELL.
